DISPENSING DEVICE

Hugh K. Ervin, Bartlesville, Okla.

Application June 5, 1935, Serial No. 25,145

2 Claims. (Cl. 221—60)

The invention relates to dispensing devices and particularly to a device for supporting and discharging tooth paste from collapsible tubes, and has for its object to provide a device of this character comprising a chambered supporting holder having a rotatable member therein, around which the bottom end of the tube is wound and compressed by a convexed spring member yieldably engaging the tube, and by rotation of the rotatable member.

A further object is to form the holder cylindrically shaped with its ends open and to provide a slit extending entirely through one side thereof and formed by opposed curved lips adapted to grip and compress opposite sides of the tube and to provide a rotatable key within the cylindrical member and around which the bottom end of the tube is wound for pulling said end of the tube between the lips for a dispensing operation.

A further object is to provide means whereby the device may be supported in various positions on a support thereby allowing the same to be used and attached to the wood work in different positions in a room.

A further object is to provide a tube compressor comprising a supporting holder having a chamber extending entirely through the same and registering compressing lips at one side thereof and between which the tube is drawn and compressed upon rotation of a key within the holder.

A further object is to provide a collapsible tube holder and compressor comprising a supported member having downwardly extending flanges at the ends thereof rearwardly recessed for the reception of the pintles of a rotatable roller and the forward upper side thereof of a downwardly and rearwardly extending compressing spring flange cooperating with the roller for compressing the tube and also forming means for maintaining the roller pintles in the recesses of the downwardly extending flanges.

With the above and other objects in view the invention resides in the combination and arrangement of parts as hereinafter set forth, shown in the drawings, described and claimed, it being understood that changes in the precise embodiment of the invention may be made within the scope of what is claimed without departing from the spirit of the invention.

In the drawings:

Figure 1 is a perspective view of the tube holder showing a tube therein.

Figure 2 is a side elevation of the holder and tube, showing the holder supported in a hori-

zontal position, and the starting of the tube collapsing operation.

Figure 3 is a side elevation of the holder and tube, showing the tube as it reaches its final compressed condition.

Figure 4 is a perspective view of the rotatable key.

Figure 5 is a front elevation of the holder and tube, showing in dotted and full lines the various positions it may assume in a vertical plane, when supported as shown in Figure 2.

Figure 6 is a perspective view of a modified form of holder.

Figure 7 is a side elevation of the holder and tube shown in Figure 6.

Figure 8 is a view similar to Figure 7 but showing the tube in final collapsed condition and one of the end flanges broken away to better show the structure.

Figure 9 is a perspective view of the rotatable key shown in Figure 6.

Referring to the drawings, particularly Figures 1 to 5, the holder comprises a cylindrically shaped member 1 having a chamber 2 extending entirely therethrough, thereby forming open ends, the purpose of which will presently appear. The member 1 is provided with nail head receiving apertures 3, preferably in pairs at ninety degrees from each other, thereby allowing the holder to be supported in a horizontal position as shown in Figure 2, or in various vertical positions according to the available wood work in a bathroom or other room in which the device is disposed.

Figure 5 shows in dotted and full lines some of the positions in a vertical plane the device may assume. It will be noted that the apertures 3 are provided with enlarged and restricted ends to receive the shank and head 4 and 5 of a supporting nail, preferably in pairs, hence it will be seen the device may be positively supported by simply passing the heads 5 of the nails through the enlarged portions of the apertures 3 and moving the member 1 longitudinally.

One side of the member 1 is provided with a longitudinally extending opening 6 formed by the curved lips 7 of the body member 1, and which curved lips have opposed curves which register with each other and are adapted to compressibly engage the opposite sides of the tube 8 and collapse the same thereby forcing the contents from the tube through the discharge neck 9 when the tube cap 10 is removed. The member 1 is formed from spring material, hence the curved lips 7 will yieldably compress the tube. The bottom end 11 of the tube 8 is first extended through the

elongated slot 12 in the rotatable key 13, which is provided with a finger engaging member 14 at one end thereof and then the key is placed within the chamber 2 of the member 1 either by a longitudinal movement of the key through one end thereof or by forcing the key between the lips 7. When it is desired to dispense paste from the tube 8 the key 13 is rotated until the tube is emptied as shown in Figure 3, and the final amount within the tube may be discharged from the neck 9 by a manual pushing inwardly of the neck end of the tube when it reaches the position shown in Figure 3.

After the tube has been completely collapsed as shown in Figure 3, it may be easily removed from the device by the operator pulling the key 13 from the chamber 2 through one of the open ends thereof and then unwinding the key and replacing the tube with a new one.

Referring to Figures 6 to 9 wherein a modified form of holder is provided, in this form the holder 15 is formed from spring sheet metal bent to provide a rear flange 16 adapted to be attached to a support 17 by means of headed members 18, which are received in apertures 19 similar to the apertures 3, so that the device may be supported in various positions. The ends of the top plate 20 terminate in downwardly extending roller supporting flanges 21, the lower ends of which are rearwardly recessed at 22 to form bearings for the reception of the pintles 23 of a rotatable roller 24, one end of which carries a finger engaging member 25. One side of the roller 24 is provided with a longitudinally extending channel 26 which receives the bottom end of the tube 8, as shown in Figure 7. The forward side of the top plate 20 terminates in a downwardly and rearwardly extending spring compressing plate 27, which engages the tube 8 adjacent one side of the rotatable roller 24 and collapses and compresses the same against the roller 24 as the roller is rotated. Figure 7 shows the initial starting of the collapsing operation, and at which time the portion 28 of the downwardly and rearwardly extending member 27 cooperates with the rear side of the roller 24 through the portion of the tube wound thereon and maintains the pintles 23 in the bearing recesses 22. After the completion of the winding operation the roller may be removed by manually forcing the member 28 rearwardly, as clearly shown in Figure 8.

From the above it will be seen that a collapsible tube compressing and dispensing device is provided which is simple in construction, positive in its operation, and one which may be cheaply manufactured and sold. It will also be

seen that the tube, after the contents have been dispensed therefrom, may be easily removed from the key or roller and replaced with a new one.

The invention having been set forth what is claimed as new and useful is:

1. A collapsible tube holder and compressor comprising a chambered supporting member comprising a wall engaging flange and a top flange, downwardly extending end flanges carried by the top flange, the rear sides of the downwardly extending end flanges being rearwardly recessed thereby forming bearings, a rotatable roller around which a tube end is wrapped between the end flanges, pinions carried by the roller and disposed within the recesses of the end flanges, the top flange at its forward side terminating in a downwardly, rearwardly and downwardly extending spring flange above and to the rear of the roller and adapted to yieldably compress a tube from the top and rear sides of the roller against the roller as it is wound thereon, the downwardly, rearwardly and downwardly extending flange terminating below the roller and forming means for forcing the roller forwardly and maintaining the pintles thereof in the bearing and means below the roller adapted to be sprung rearwardly manually for allowing removal of the pintles of the roller from the bearings after the tube collapsing operation.

2. A collapsible tube holder comprising a rear plate adapted to be secured to a support, an outwardly extending plate carried by the upper end of the rear plate, downwardly extending flanges carried by the ends of the rear plate and the end of the upwardly extending flange, a roller beneath the outwardly extending flange and between the downwardly extending end flanges, said roller having pintles rotatably mounted in recesses in the downwardly extending end flanges, said recesses having their rear sides open for removal of the roller, the forward end of the outwardly extending flange terminating in a downwardly extending compression lip curving rearwardly from a position forwardly of the vertical longitudinal center of the roller and thence downwardly rearwardly of the roller and terminating spaced from the rear side of the roller and adjacent the horizontal plane of the under side of the roller within reach of the fingers of the operator, said downwardly extending compression lip forming means cooperating with a tube wrapped around the roller for compressing a tube against the roller and forcing the contents therefrom.

HUGH K. ERVIN.
